UNITED STATES PATENT OFFICE

92,161

DESIGN FOR A COMBINATION SIGNAL LIGHT AND ASH TRAY

Lawrence F. Brown, Oakwood, Ohio

Application February 27, 1934, Serial No. 50,893

Term of patent 14 years

To all whom it may concern:

Be it known that I, LAWRENCE F. BROWN, a citizen of the United States, residing in the city of Oakwood, in the county of Montgomery and State of Ohio, have invented a new, original, and ornamental Design for a Combination Signal Light and Ash Tray, of which the following is a specification, reference being had to the accompanying drawing, forming part hereof.

The figure is a perspective view of a combination signal light and ash tray, showing my new design.

I claim:

The ornamental design for a combination signal light and ash tray, as shown.

LAWRENCE F. BROWN.
